UNITED STATES PATENT OFFICE.

ALFRED J. FLAUDER, OF BRIDGEPORT, CONNECTICUT, ASSIGNOR TO THE WEIDLICH BROS. MFG. CO., OF BRIDGEPORT, CONNECTICUT, A CORPORATION OF CONNECTICUT.

DESIGN FOR A LAMP PERFUMER.

Application filed March 19, 1923. Serial No. 5,526. Term of patent 7 years.

To all whom it may concern:

Be it known that I, ALFRED J. FLAUDER, a citizen of the United States, and a resident of Bridgeport, in the county of Fairfield and State of Connecticut, have invented a new, original, and ornamental Design for a Lamp Perfumer, of which the following is a specification, reference being had to the accompanying drawing, forming a part thereof, and in which,

Fig. 1 shows a front perspective view of my novel design, and

Fig. 2 shows a top plan view of the same.

I claim:

The ornamental design for a lamp perfumer, substantially as shown.

Signed at Bridgeport in the county of Fairfield and State of Connecticut this 16th day of March, A. D. 1923.

ALFRED J. FLAUDER.
